UNITED STATES PATENT OFFICE.

JOHN W. TOWNSEND, OF NEW YORK, N. Y., ASSIGNOR TO AMERICAN LITHOGRAPHIC COMPANY, OF NEW YORK, N. Y., A CORPORATION OF NEW YORK.

STACK SUSTAINING AND SEPARATING DEVICE.

Application filed September 29, 1923. Serial No. 665,620.

To all whom it may concern:

Be it known that I, JOHN W. TOWNSEND, a citizen of the United States, and a resident of New York, borough of Bronx, in the county of Bronx and State of New York, have invented certain new and useful Improvements in Stack Sustaining and Separating Devices, of which the following is a specification.

10 This invention relates to stack sustaining and separating devices, and has for its object to provide a device of the class specified, simple in construction and efficient in operation. Particular features of adaptability and efficiency will be pointed out in detail herein.

The preferred embodiment of my improvements is shown in the accompanying drawing, wherein:—

20 Figure 1 is a plan view of so much of a guillotine paper cutter as will suffice to illustrate the use of my device, to which it is applied. Fig. 2 is a front elevation corresponding with Fig. 1, except the clamp bar is omitted. Fig. 3 is a fragmentary vertical section on line 3—3 of Fig. 1. Figs. 1 and 2 are to one scale and Fig. 3 is to a much larger scale.

25 The present improvements are particularly directed to facilitating the handling of stacks of strips of sheet material, such as paper or cardboard, in a cutting press, in which said strips are to be cut into short lengths. The device is particularly adapted for use in connection with the cutting up of sheets, previously printed with a plurality of regularly arranged designs, into an equal plurality of cards, each bearing one of said designs.

40 The cutting of said sheets into strips is a relatively simple operation and is antecedent to the use of my improvements. The maintenance of a row of piles of stacks of strips, particularly if said strips be 45 narrow, is attended with considerable difficulty and commonly results in more or less waste due to the shifting of the piles under the successive clamping and releasing of the clamp bar. This also causes the stacks 50 to interleave and otherwise to get out of register. The draw or drag of the descending knife also disarranges the free ends of the stacks, even when those stacks are clamped to the table. My improved device

efficiently obviates these several difficulties 55 and reduces the spoilage to a minimum.

Directing attention now to the drawing, side frames 2, 4 of the cutting press are adapted for guiding knife 5 for vertical and angular reciprocation. Directly behind knife 5 is bar 6 adapted for clamping a stack of sheets or several stacks of strips, as 7, 8, 9, onto table 10 near the front ends of said stacks. At the rear ends of said stacks is back gage 11 comprising the usual 60 row of forwardly reaching fingers, as 12, 12. Said back gage is moved forwardly from time to time toward knife 5 for urging said stacks of strips under said knife, in position for being cut. 70

My improved sustaining and separating device comprises means for engaging the upper faces of the stacks and the end of that stack most remote from side frame 2, against which the left hand stack of the 75 row of stacks is closely pressed, the succeeding rows standing snugly against their next left hand adjacent stack, respectively. Said means for engaging said upper faces and said right hand end comprises an angular frame 13 which may conveniently be formed of top member 13^a and end member 13^b, held together by screws, as 14. Top member 13^a has a length slightly less than the aggregate width of a given plurality of 80 strips, such for instance as the width of the sixteen strips shown. End member 13^b has a height slightly less than the height of a stack, as stack 9. Top member 13^a is held in operative position on top of the 85 stacks of strips and adjacent their rear ends by means of one or more arms, preferably two, 15, 16, which may be secured to said member 13^a by screws, as 17. Said arms extend rearwardly from member 13^a and 90 each removably engages two adjacent fingers, as 12, 12, respectively, of back gage 11. By this means said frame 13 is held securely 95 in position against the top and right hand end of the bank of stacks. Top member 13^a 100 is provided with a series of narrow slots, as 18, 19, 20, extending inwardly from its front edge and penetrating about half the width of said member. Said slots correspond in number and position with the 105 divisions between the several stacks and are adapted to receive blades, as 21, 22, 23, and to guide and sustain those blades in vertical

positions, respectively. Said blades are adapted and efficient for penetrating downwardly between two adjacent stacks, as blade 23 between stacks 7 and 8, for holding those stacks in vertical position and for preventing their interleaving.

Said frame 13 and blades, as 23, in maintaining the rear ends of the stacks in position, provide a reference for resetting from time to time the front ends of the stacks, where they are being cut, and which front ends become more or less deranged by the drag of the knife even though those front ends are held down by bar 6.

15 While only three blades, 21, 22, 23, are shown, it will be understood that more blades may be used between other contiguous pile edges if desired. When the strips are very narrow a greater number of blades 20 are used.

It will also be understood that a different frame 13 is needed when narrower or wider strips are to be cut, and that the spacing of the slots, as 18, 19, 20, is made to correspond with the width of said narrower or wider strips. As said frame is preferably constructed of wood and is of small cost, such duplicate frames, corresponding in slot spacing with various requirements, can be 30 kept on hand.

I claim:

1. In a device of the character specified the combination of a frame adapted for engaging the top and end of a plurality of 35 stacks of strips arranged side by side, means for holding said frame in operative position, said frame having a vertical slot therethrough, and a blade having a thickness adapted for filling said slot widthwise, said 40 blade being adapted for penetrating downwardly between two adjacent stacks for separating said stacks and for maintaining them in position.

2. In a device of the character specified 45 the combination of a frame adapted for engaging the top and end of a plurality of stacks of strips arranged side by side, means for holding said frame in operative position,

said frame having a plurality of vertical slots therethrough, and a plurality of blades 50 adapted for entering said slots respectively and being sustained in vertical position thereby, said blades being efficient for penetrating downwardly between said stacks respectively for separating said stacks and for 55 maintaining them in upright position.

3. In a device of the character specified the combination of a frame comprising a top member and an end member adapted for engaging the top and end respectively of a 60 plurality of stacks of strips arranged side by side, a back gage, means carried by said frame for engaging said back gage for holding said frame relatively to said stacks of strips, said top member having a plurality of 65 vertical slots therethrough and the spacing of said slots corresponding with the width of said strips, and a plurality of blades adapted for entering said slots respectively and being sustained in vertical position 70 thereby, said blades being efficient for penetrating downwardly between said stacks respectively for separating said stacks and for maintaining them in upright position.

4. In a device of the character specified 75 the combination of a frame comprising a top member and an end member adapted for engaging the top and end respectively of a plurality of stacks of strips arranged side by side, a back gage having a plurality of 80 forwardly reaching fingers, an arm fixed to said top member for removably engaging two adjacent fingers of said back gage, said top member having a plurality of vertical 85 slots therethrough and the spacing of said slots corresponding with the width of said strips, and a plurality of blades adapted for entering said slots respectively and being sustained in vertical position thereby, said blades being efficient for penetrating downwardly between said stacks respectively for 90 separating said stacks and for maintaining them in upright position.

In witness whereof, I hereby affix my signature this 26th day of September, 1923.

JOHN W. TOWNSEND.
